VAPOR SEPARATOR

Lloyd E. Johnson, Peoria, Ill., assignor to Caterpillar Tractor Co., San Leandro, Calif., a corporation of California

Application May 29, 1946, Serial No. 673,185

2 Claims. (Cl. 137—69)

1

This invention relates to vapor separators and more particularly to devices employed to separate vapors or gases from liquid in a closed system and to permit the vapors to escape from the system without permitting the escape of liquids.

Vapor separators are often desirably employed in connection with fuel systems in internal combustion engines as the more or less volatile fuels used in such engines give off large quantities of vapor which unless separated from the liquid fuel will under some conditions interfere with proper functioning of the engine. The vapor separator herein disclosed is of a type which can be readily used in such a fuel system though its adaptability to other uses will be apparent from the disclosure which follows.

It is an object of this invention to provide a vapor separator which is simple in construction and positive in operating and in which a closely fitting liquid tight valve is easily operated by a small float buoyantly suspended in the liquid from which the vapor is separated. Further and more specific objects and advantages of the invention are made apparent in the following specification wherein a preferred form of the invention is described by reference to the accompanying drawings.

In the drawings:

Fig. 1 is a vertical sectional view through a vapor separator chamber within which is disposed a vapor separator embodying the present invention;

Fig. 2 is a fragmentary sectional view taken on the line II—II of Fig. 1;

Fig. 3 is a similar view taken on the line III—III of Fig. 1; and

Fig. 4 is a fragmentary sectional view taken on the line IV—IV in Fig. 1.

In Fig. 1 of the drawings the vapor separator of the present invention is disclosed as contained within a housing 4 which forms a liquid chamber 6 into which fuel or other liquid from which vapor is to be separated may be directed as through a supply line 7. The housing 4 may also be provided with a discharge line not shown or may be in communication with another tank or housing forming a part of a fuel system or the like. A float 8 preferably in the form of a hollow metal body of any desired shape is disposed within the chamber 6 of the housing and is suspended from a rotatable valve element 9 by means of a bracket 11. The bracket 11 is shown as rigidly secured to a sleeve 12 which fits over a cylindrical stem portion of the valve element 9 and is secured against rotation with relation thereto as by a pin indicated at 15.

2

When liquid entering the chamber 6 attains a level sufficiently high to raise the float 8, a rotary motion is imparted to the valve element 9. The element 9 is journaled for rotation in a non-rotatable valve sleeve 16 which projects into the chamber 6 and is carried by a cover member 17. The cover 17 closes an opening at one side of the chamber of sufficient size to permit removal of the separator valve and float. A pin 18 disposed within the cover 17 engages a notch 19 formed in an enlarged portion of the sleeve 16 to prevent rotation of the sleeve. Cap screws such as indicated at 21 in Fig. 1 retain the cover in place and a suitable gasket 22 may be employed 15 for providing a fluid tight connection between the cover and the housing. A cap 23 is secured to the cover member 17 by screw means or the like, not shown, and abuts the enlarged portion of the valve sleeve 16 to prevent its endwise movement 20 with relation to the housing and this cap forms a point of connection for a vapor discharge line shown at 25 which may direct escaping vapors to the atmosphere or to a suitable disposal chamber, not shown. A bushing 24 is shown as employed at the connection between the line 25 and the cap 23.

The valve sleeve 16 is provided with a milled slot or aperture 28 forming a passage for the communication of vapors from its outer surface to its inner surface and a similar slot 29 is formed in the valve element 9 and communicates with a longitudinal bore 31 which extends to an end of the valve element. A sleeve 32 rotatably embraces the portion of the valve sleeve 16 which extends into the chamber 6, and radial ports 33 (see Figs. 1 and 2) in this sleeve communicate with a channel 36 which circumscribes the valve sleeve 16 and which also registers with the slot 28 formed therein. One function of the sleeve 32 is to prevent splashing liquid in the chamber 6 from escaping too readily through the vapor outlet which is provided by the slots 28 and 29 when they are in registry with each other.

45 In the operation of the structure so far described, liquid entering the chamber 6 through the supply line 7 will cause the float to rise through its buoyancy to the position illustrated in Fig. 2 in which position the valve element 9 has been rotated by its connection with the float to a point where its slot 29 is out of registry with the slot 28 in the valve sleeve 16. Thus, any liquid which enters the slot 28 through the channel 36 and the ports 33 in the sleeve 32 cannot escape through the longitudinal bore 31 of the valve member 9. If, on the other hand, the liquid en-

tering through the supply line 7 contains vapors or gases, such vapors or gases will rise in the chamber 6 and by their occupancy of the upper portion of such chamber will prevent the liquid level of the chamber from rising to a point where it will actuate the float 8. Consequently, the float will depend by gravity to a position in which the slot 29 of the valve element registers with the slot 28 of the valve sleeve and the vapors in the upper portion of the chamber 6 will be free to escape through ports 33 and channel 36 and eventually into the bore 31 of the valve element from which they may pass, as will presently appear, to the vent line 25. The valve element is preferably very closely fitted within the valve sleeve 16 so that even volatile liquids will not escape when the valve element is rotated to its closed position as illustrated in Fig. 2. Even though this closeness of fit offers some resistance to the turning of the valve element, the arrangement of the float is such that considerable leverage is obtained and the force applied in rotating the valve element as the liquid level rises in the chamber 6 is much greater than that afforded by the buoyancy of the float alone. The slots 28 and 29 extend longitudinally with relation to the cylindrical ports in which they are formed so that upon registering with each other a relatively large port is provided for the escape of vapors.

Endwise movement of the valve element 9 is prohibited by a collar 41 received in a suitable groove circumscribing the valve element as shown in Figs. 1 and 4 and the collar 41 bears against the end of the valve sleeve 16. The collar is notched as indicated in Fig. 4 so that it may be slipped onto the shaft and the assembly of the cap 23 in the position shown in Fig. 1 serves to prevent its removal therefrom. This prevents axial movement of the valve element 9 in one direction. Axial movement in the opposite direction may be induced by pressure of fluid within the chamber 6 on the end of the valve element 9 and a thrust bearing with a free moving bearing surface is provided by disposing a ball 42 in a conical recess in the end of the valve element. The ball 42 is retained in place by a cup like retainer 43 which may be press fitted over the end of the element 9 and which has a central perforation to permit the ball to protrude and bear against a disc like plate 44 disposed within the cap member 43. The ball 42 provides a bearing surface of small area which absorbs the thrust of the valve element 9 so that even though the valve element may be pressed outwardly by the pressure of fluids within the chamber 6, its freedom to rotate will not be materially hindered by this thrust engagement. A plurality of orifices 46 are provided in the disc 44 to permit vapors to pass through it toward the vent line 25. Orifices 47 shown in Figs. 1 and 4 communicate between the longitudinal bore 31 of the valve element 9 and the circumscribing groove within which the collar 41 fits and permit the exit of vapors from the bore of the valve element toward the vent line.

The proper operation of the vapor separator as it is thus far disclosed depends upon its being disposed in a substantially vertical position so that gases entering the chamber 6 and separat-

ing from the liquid therein will rise toward the top of the chamber and effect downward swinging movement of the float. This movement opens the valve to vent the gases. It is conceivable, however, that the vapor separator may be inverted in operation as, for example, if it is used on an aircraft engine and the aircraft were temporarily flying upside down. In this event, the liquid within the chamber 6 would occupy that portion of the chamber which is shown in Fig. 1 as the upper portion and the float would be swung to its Fig. 1 position not by gravity as indicated in Fig. 1 but by buoyant effect of the liquid upon it. Escape of liquid through the vapor separator valve is prevented in such an event by a pendulum shown at 37 which is secured to the rotatably mounted sleeve 32 and carrying a lug 38 which projects to a position for engagement with the float 8. In the event that the entire vapor separator is inverted, the pendulum 37 will fall by gravity and the lug 38 by engagement with the float 8 will hold the float in what is normally its upward or valve closing position, which position is illustrated in Figs. 2 and 3. The weight of the pendulum is sufficient to overcome the buoyant effect on the float of the liquid in the chamber 6 and therefore the valve is maintained in its closed position and liquid is prevented from entering the vent passage which is intended only for the escape of vapor.

I claim:

1. In a vapor separator a chamber, a vapor venting valve comprising, a tubular valve sleeve, a valve element rotatable in said sleeve, ports in said element and sleeve adapted to register upon rotation of the element to permit the escape of vapor, a float carried by the valve element for actuation thereof by liquid in the chamber, and a sleeve embracing the valve sleeve and having a port out of register with the port of the valve sleeve but connected therewith by passage means to prevent the escape of splashing liquid through the valve when it is open.

2. In a vapor separator a chamber, a normally open vent valve adjacent the upper end of the chamber, a pivoted float adapted to rise and close said valve upon the rise of liquid level in the chamber, and weight means pivoted coaxially with the float and engageable with the float to retain it in its valve closing position in the event the chamber is inverted.
